UNITED STATES PATENT OFFICE

GEORGE GARDNER, OF REDLANDS, CALIFORNIA

LOADING ATTACHMENT FOR GRADERS

Application filed February 15, 1928. Serial No. 254,429.

This invention relates to road working machinery, and more particularly to that class of road working machines ordinarily termed "graders."

An object of the invention is to provide an attachment for graders whereby the dirt scraped to one side by the scraper blade, may be automatically lifted and dumped into a vehicle.

10 A more specialized object is the provision of a bucket conveyor adapted to be positioned upon the chassis of a grader so as to enable the buckets thereof to scoop up, elevate and dump into a suitable vehicle, the dirt which 15 has been scraped to one side by the scraper blade of the grader.

A further object is the provision of a conveyor as above described, which is adapted to be positioned upon any grader of conventional design.

20 A further object is the provision of a device of the character described, having incorporated therewith, various adjustments permitting alterations in the elevation and 25 reach of the conveyor, and permitting the scraper blade to be adjusted to different degrees of angularity with the longitudinal axis of the grader.

It is a further object of my invention to 20 provide a combined grader and elevator and conveyor which is simple and rugged in structure, is relatively inexpensive to manufacture, and is speedy and positive in operation.

35 With the foregoing and other objects in view which will be made manifest in the following detailed description and specifically pointed out in the appended claims, reference is had to the accompanying drawings for an 40 illustrative embodiment of the invention, wherein:

Figure 1 is a perspective view of a combined grader and conveyor of my invention.

Fig. 2 is a side elevation of the conveyor 45 and the after end of the grader of Fig. 1, the direction of view being indicated by the arrow 2 of Fig. 3, a portion of the figure being broken away to reduce its length.

Fig. 3 is a transverse, sectional view of the 50 grader and conveyor, the plane of section be-

ing taken upon the line 3—3 of Fig. 2 in the direction of the arrows.

In terms of broad inclusion, the device of my invention comprises mechanism adapted to be supported upon the chassis of a road 55 grader, and to scoop up the dirt deposited at one side by the blade of the grader, and to lift the dirt to a suitable elevation to enable it to be dumped into a vehicle.

In greater detail, the present embodiment 55 of my invention is shown mounted upon the chassis 6 of a conventional road grader, having a scraper blade 7 depending from the chassis 6. In accordance with the usual design of graders, the blade 7 is capable of vertical adjustment. For this purpose a pair of hand wheels 8 are mounted upon the chassis 6, in position to be operable from the operator's platform. Each of the hand wheels 8 is operatively connected to a crank 9 by gearing 9' (see Fig. 2) and each of these cranks 9 is connected by a link 10 to the associated end of the structure upon which the blade 7 is supported. This structure comprises a ring 10' which is rigid with a rail 10" extending longitudinally of the chassis 6, and a ring 23 which is revolvably disposed upon the ring 10' and guided for rotation with respect thereto, by a plurality of brackets 23' which are rigid with the ring 10' and extend loosely about the lower edge of the ring 23. The blade 7 is suspended from the revolvable ring 23 in the well-known manner, by a plurality of arms 7'. The forward end of the rail 10" is pivoted to the chassis 6, 85 and the after end is guided by mechanism (not shown) for vertical movement, but is restrained against movement transversely with respect to the chassis 6. It is therefore apparent that by operating one of the hand wheels 8, the associated end of the blade 7 may be raised or lowered independently of the other end, the brackets 23' being sufficiently loose to permit a certain amount of swinging of the ring 23 about a horizontal 95 axis extending longitudinally of the chassis 6 and with respect to the stationary ring 23. Similarly, by operating both hand wheels 8 the entire blade may be adjusted vertically. The blade 7 is also capable of being adjusted 100

to different degrees of angularity with the longitudinal axis of the grader by being operatively connected to a similar hand-wheel also accessible from the operating platform. This mechanism is of the type conventionally employed upon road graders, and the details thereof have therefore not been shown. It is to be understood that such graders operate by being drawn along the surface to be graded, the blade 7 being adjusted to either horizontal position or at any desired angularity with the horizontal, at suitable elevation above the surface to be graded, and with one end of the blade in advance of the other so that dirt engaged by the blade will be pushed to one side.

My invention contemplates a conveyor combined with such a grader, whereby the dirt may be lifted as it accumulates at the after end of the blade 7, and elevated sufficiently to permit the disposition thereof in a suitable vehicle. For this purpose I provide a frame comprising a pair of spaced side members 11 connected at each end by a shaft 12 revolvably mounted therein. A pair of sprockets 13 are mounted upon each of the shafts 12, and a pair of endless chains 14 are carried by these sprockets. A plurality of conveyor buckets 16 are disposed throughout the entire length of the chains 14.

The lower of the two shafts 12 is extended at each end to be revolvably mounted within a journal 21 which is supported upon an auxiliary frame 22, which in turn is rigidly secured to the circular frame 23 from which the blade 7 of the grader depends, and which, as explained hereinabove is mounted for pivotal movement about a vertical axis with respect to the stationary ring 10' for the purpose of varying the degree of angularity of the blade 7, as well as being capable of vertical adjustment as previously indicated. It may thus be seen that the lower end of the conveyor is supported closely adjacent a point at which dirt is discharged from the after end of the scraper 7, being mounted rigidly for movement therewith. Preferably the associated link 10 is connected directly to the auxiliary frame 22, the other link 10 being left with its normal connection to the circular frame 23. Also, the mounting of the lower end of the conveyor is of such a nature that pivotal movement of the conveyor about a horizontal axis adjacent its lower end is possible.

A pair of brackets 24 are rigidly secured to the top of the chassis 6, and are rigidly joined by a bar 25 which has pivoted thereon by means of a bolt 26, a piece of angle iron 27 corresponding in length to the width of the conveyor. A link 28 is pivoted to each end of the angle iron 27, each link 28 being provided with a plurality of holes 29 for the reception of a bolt 31 extending through each of the side members 11. Thus by engaging

the bolt 31 in a different one of the holes 29, the reach, or degree of angularity, of the conveyor may be altered. It is to be understood that the pivot 26 is in substantially vertical alignment with the vertical axis about which the frame 23 is adapted to turn. An open-ended trough 34 is carried by the auxiliary frame 22 surrounding the lower end of the conveyor; this trough being positioned to receive dirt discharged from the blade 7 and preferably being riveted or otherwise directly and rigidly connected thereto in line therewith, so as to confine the dirt within an area where it may be conveniently picked up by the buckets 16 as they pass through the trough around the lower sprockets 13. Moreover, the bottom of the trough is at substantially the same level as at the lowermost edge of the blade 7, with the result that the dirt discharged from the blade, is deposited therein. It is evident therefore, that the normal operation of the blade 7 is in no manner interfered with, the dirt naturally falling into the trough from the after end of the blade instead of accumulating in an elongated windrow. Furthermore, no alteration of the blade 7 is required to satisfactorily mount the elevator of my invention in operative position theradjacent. For the purpose of imposing the desired degree of tension upon the chains 14, the journals within which the upper shaft 12 is revolvably mounted, are slidably vertically within guideways 36. A rod 37 is threaded through a nut 38 and extends downwards on each side of the conveyor frame to have its lower end engaged within one of the journals within which the shaft 12 rotates, so that by turning the rods 37 in the proper direction, the shaft 12 may be elevated or lowered, varying the tension upon the chains 14. A sprocket 39 is rigidly mounted upon the outer end of the upper shaft 12, and is connected by an endless chain 40 to a sprocket 41 carried upon a shaft 42 journaled also upon the frame of the conveyor.

A beveled gear 43 is carried by the shaft 42 and is enmeshed with a beveled gear 44 upon a shaft 46 which is connected through a clutch 47 to a motor 48 which is rigidly supported upon the chassis 6 of the grader. A chute 51 is supported adjacent the upper end of the conveyor by arms 52 whereby dirt dumped from the buckets 16 as they pass over the upper sprockets 13, may be conveyed to a point sufficiently spaced from the grader to permit the disposition thereof within suitable vehicles.

It is evident that if the weight of the entire conveyor, as well as one-half the weight of the blade 7, were to be supported solely upon the link 10 and crank 9 associated with that end of the blade 7 from which dirt is discharged into the trough 34, considerable difficulty might be caused in the operation of

the associated hand wheel 8 to vary the vertical adjustment of that end of the blade and the conveyor. Consequently, I have provided means for supporting at least a portion 5 of this weight through the expedient of a counter-weight 56 which depends by means of a cable 57 upon the opposite side of the chassis 6. This cable 7 passes over sheaves 58 and 59 journalled upon the chassis 6 around another sheave 61 journalled upon 10 the auxiliary frame 22, and carried upwards therefrom to be made fast to the chassis 6 at any convenient location. It is readily apparent that this will assist in the operation of 15 the associated hand wheel 8.

Briefly, the operation of my device is as follows: The grader is drawn along the surface to be graded, with the blade 7 in the proper position to engage the dirt and discharge it into the trough 34. The conveyor is driven by the motor 48, shaft 46, shaft 42, chain 40, and sprocket 39, so that the buckets 20 pass through the trough 34 successively, picking up the dirt there deposited. As the buckets 25 pass over the upper sprocket 13, the dirt is dumped from the buckets into the chute 51, and conveyed to a point where it may be deposited into suitable vehicles. It should be observed that the conveyor and 30 chute 51 extend laterally from the grader, thus making it convenient for trucks to travel alongside the grader and receive the dirt directly from the chute 51, avoiding the necessity of additional labor or the employment 35 of other machines to load the trucks.

Various changes in the details of construction may be made without departing from the spirit and scope of the invention as defined by the appended claims.

I claim:

1. In combination, a grader comprising a chassis, a frame mounted for pivotal movement about a vertical axis on said chassis, and a horizontal blade carried by said frame; and a conveyor mounted adjacent its lower end on said frame and mounted adjacent its upper end for pivotal movement about a vertical axis on said chassis.

2. In combination, a grader comprising a chassis, a frame mounted for pivotal movement about a vertical axis on said chassis, and a horizontal blade carried by said frame; and a conveyor mounted adjacent its lower end on said frame and mounted adjacent its upper end for pivotal movement about an axis in vertical alignment with the axis of said frame.

3. In combination, a grader comprising a chassis, a frame mounted for pivotal movement about a vertical axis on said chassis, and a horizontal blade carried by said frame; a conveyor pivotally mounted adjacent its lower end on said frame and mounted adjacent its upper end for pivotal movement about a vertical axis on said chassis, and

means for altering the elevation of the upper end of said conveyor.

4. In combination, a grader comprising a chassis, a frame mounted for pivotal movement about a vertical axis on said chassis, and a horizontal blade carried by said frame; a conveyor pivotally mounted adjacent its lower end on said frame, a bracket rigid with said chassis, and a link pivoted at one end adjacent the upper end of said conveyor and pivoted at the other end to said bracket.

5. In combination, a grader comprising a chassis, a frame mounted for pivotal movement about a vertical axis on said chassis, and a horizontal blade carried by said frame; a conveyor pivotally mounted adjacent its lower end on said frame, a bracket rigid with said chassis, a link pivoted at one end adjacent the upper end of said conveyor and pivoted at the other end to said bracket, and means for altering the effective length of 85 said link.

6. In combination, a grader comprising a chassis, a frame carried by said chassis, a horizontal blade carried by said frame, and means for altering the elevation of said frame; and a conveyor comprising a frame, a shaft extending transversely of said frame adjacent each end thereof, a sprocket on each shaft, an endless chain carried by said sprockets, buckets on said chain, and means for rotating said shafts, said conveyor being supported at its lower end upon said blade frame and adjacent its upper end upon said chassis.

7. In combination, a grader comprising a chassis, a frame carried thereby, a blade carried by said frame, and means for altering the elevation of said frame; and a conveyor comprising a frame pivoted at its lower end to said blade frame adjacent one end of the blade, a shaft extending transversely of said conveyor frame adjacent each end thereof, a sprocket on each shaft, an endless chain carried by said sprockets, buckets on said chain, means for rotating said shafts, and a link pivotally connected at one end to said chassis, and at the other end adjacent the upper end of said conveyor frame.

8. In combination, a grader comprising a chassis, a frame carried thereby, a blade carried by said frame, and means for altering the elevation of said frame; and a conveyor comprising a frame pivoted at its lower end to said blade frame adjacent one end of the blade, a shaft extending transversely of said conveyor frame adjacent each end thereof, a sprocket on each shaft, an endless chain carried by said sprockets, buckets on said chain, means for rotating said shafts, and a link pivotally connected at one end to said chassis, and at the other end adjacent the upper end of said conveyor frame.

9. In combination, a grader comprising a chassis, a frame carried thereby, a blade car-

ried by said frame, and means for altering the elevation of said frame; and a conveyor comprising a frame pivoted at its lower end to said blade frame adjacent one end of the blade, a shaft extending transversely of said conveyor frame adjacent each end thereof, a sprocket on each shaft, an endless chain carried by said sprockets, buckets on said chain, means for rotating said shafts, a link pivotally connected at one end to said chassis, and at the other end adjacent the upper end of said conveyor frame, and a counterbalance operatively connected to said blade and conveyor frame for supporting a portion of the weight thereof.

10. In combination with a road grader comprising a chassis and a blade carried thereby in oblique angularity with the direction of travel of said grader; and a conveyor mounted on said chassis and comprising a trough rigid with said blade and positioned in alignment with the lower edge of said blade, and means for conveying dirt from said trough.

20. 11. In combination with a road grader comprising a chassis and a blade carried thereby in oblique angularity with the direction of travel of said grader; and a conveyor mounted on said chassis and comprising a trough rigid with said blade and positioned in alignment with the lower edge of said blade, a frame mounted for pivotal movement about a horizontal axis above said trough, and a conveyor carried by said frame and comprising buckets adapted to dip into said trough as they travel upon the frame, and means for actuating said conveyor.

25. 12. In combination, a road grader comprising a chassis and a scraper blade carried thereby and adapted to discharge dirt from an end thereof; and an elevator carried by said chassis in position to receive dirt directly from said blade, and comprising a plurality of buckets mounted for movement in a path extending from closely adjacent said blade, means for actuating said elevator, and a trough fastened to said blade and extending therefrom in alignment with the discharge end thereof, said trough defining said path of the buckets in moving past the end of said blade.

In testimony whereof I have signed my name to this specification.

GEORGE GARDNER.
